UNITED STATES PATENT OFFICE

CARL E. ANDERSON, OF EAST ORANGE, NEW JERSEY, ASSIGNOR TO EASTERN TOOL & MFG. CO., OF BLOOMFIELD, NEW JERSEY

CIGARETTE CASE

Application filed July 23, 1930. Serial No. 470,109.

This invention relates to an improved cigarette case in which the cigarettes from a package or the package full of cigarettes, in the latter case after tearing off the top, are held in a closed case to protect them and also to keep them from drying out and from losing their strength or aroma.

The invention comprises a case with a top which has a lid hinged to it. The top is provided with a wire which forms a strengthening rib around the edge, serves to hold the lid at its hinged edge and also serves as a latch to hold the free end of the lid shut.

The invention also comprises a case which has a flexible bottom. This allows the cigarettes to be projected slightly from the top of the case to allow one to be grasped. This is economical because the cigarettes are not broken or torn and can all be extracted undamaged especially when a full or nearly full case is manipulated. When the original package is inserted into the case with the cigarettes in it, the upper edge of the case holds the package down and only the cigarettes are lifted to a point where one can be selected and withdrawn with ease. The cigarettes are not all projected the same distance as the flexibility of the bottom is of course greatest at the centre so that the middle of the pack projects the farthest. After the pack has been reduced in numbers the cigarettes are more easily withdrawn and can be shaken out if it is not desired to elevate them by pressing on the bottom. The whole body portion or sack part of the case can be made of flexible material as thin leather, or rubber or like material or the sides can be of stiffer material such as sheet metal and only the bottom made of flexible or pliable material.

The invention is illustrated in the accompanying drawing in which Figure 1 is a front view of my improved cigarette case showing the right hand half in section. Figure 2 is a side view of the case showing the upper part as a central transverse section. Figure 3 is a perspective view of the frame at the top of the case and Figure 4 is a perspective view of the lid that closes the frame shown in Figure 3.

The case comprises a support which consists of a frame 10 and a lid 11. Suspended from the frame is a bag or sack 12 which is of a size to receive a conventional or standard size paper cigarette pack 13. The sack 55 has a flexible bottom 14 which allows the thumb to press the cigarettes up in order that one cigarette can be easily grasped and extracted without tearing it. The dotted line at 15 in Figure 1 shows the bottom as 60 forced upwardly and the dotted outline at 16 shows the top end of the protruding cigarettes. This is of particular advantage with a full or nearly full package of cigarettes as the original package does not ride up with 65 the cigarettes but is retained in place. The cigarettes 17 are shown in full lines as they are when pushed back into the case.

The frame 10 consists of a wire 18 bent into a rectangular loop and supporting a 70 thin sheet metal flange 19 which is bent over and around the wire and crimped over the top edge of the sack 12 by the two wings 20 and 21 of the flange. The frame is fairly 75 stiff but yields slightly under pressure at the opposite sides. The finger piece 22 provides space for pressing by the thumb. The fold of the flange is cut away here and there to provide for securing the lid. The cut-away part at 23 exposes the wire at 24 to allow it 80 to be engaged by the catch of the lid 11. The cut-away portions at 25 expose the wire to allow the knuckles of the lid to be bent around wire. The wire thus acts as a stiffener, as a catch for the lid and also as a hinge 85 for the lid.

The lid 11 has the latch piece 26 to engage the wire at 24 when the lid is pressed to closed position. The knuckles 27 are bent around the wire in the openings 25 to complete the hinge of the lid. One of the knuckles can be made shorter than its opening to provide space for the spring 28 to snap the lid open when released.

It will be evident that the construction of 95 the top piece provides for easy manipulation and a cheap and simple construction.

The bulge or overhang when the flange is bent around the wire 18 offers an obstruction for the original package when it is pushed 100

up by the forcing of the bottom 14 and as the bottom of the original package is paper it also flexes under upward pressure and only the cigarettes appear, as at 16, when the bottom 14 is pushed up.

5 The top of the original package 15 is torn off before the package is inserted in the bag 13.

I claim:—

- 10 1. In a case, a frame consisting of a wire looped to form a support, a metal flange folded over the wire and having openings to expose the wire, and a lid having a knuckle to engage the wire at an exposed place and a latch to engage the wire at another exposed place.
- 15 2. In a case, a frame consisting of a wire formed into rectangular loop, a flange folded over the wire and having its wings adapted to grasp the top of a bag, a bag with its top between said wings, the flange having parts cut away to expose the wire, a lid with knuckles to engage the wire at an exposed place, and a latch on the lid to engage the wire at an exposed place, the wire having sufficient resiliency to release the latch when the frame is slightly compressed.
- 20 3. A cigarette case for receiving an original package of cigarettes, the case comprising a flexible bag with a normally flat bottom and straight sides, a rectangular frame consisting of a wire, a lid hinged at one side to the wire, and a metal flange folded over the wire and having wings grasping the top of the wire, the folded part extending partly over the inside of the bag to form a bulged part to retain the package in the bag and to present a smooth surface for the passage of a cigarette when the bottom of the bag is pushed up.
- 25 4. In testimony whereof he affixes signature.
- 30 CARL E. ANDERSON.
